GARMENT SLEEVE

Charles Solomon, New York, N. Y.

Application November 24, 1945, Serial No. 630,649

2 Claims. (Cl. 2—269)

1

This invention relates to new and useful improvements in garment sleeves, and has more particular reference to sleeves with slits, such as generally used in shirts.

More specifically, the invention proposes to characterize the new and improved sleeve by the fact that it has a hem bent upwards and inwards from the outer end of the sleeve and associated with releasable means by which it may be let out or moved inwards, quite easily, for changing the length of the sleeve. It is also proposed to arrange a sleeve length scale upon the inner face of the sleeve by which the length of the sleeve may be noted and varied as desired.

The invention contemplates more than one way of releasably holding the hem so that it may be easily let out or moved inwards.

Another object of the invention is the construction of an article as mentioned which is simple, and durable, and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a fragmentary perspective view of a garment sleeve constructed in accordance with this invention.

Fig. 2 is a perspective view of the sleeve shown in Fig. 1 with the slit opened.

Fig. 3 is a fragmentary enlarged sectional view taken on the line 3—3 of Fig. 1.

Fig. 4 is a fragmentary elevational view of the inner face of that portion of the sleeve having the slit, this view being taken as though looking in the direction of the line 4—4 of Fig. 1.

Fig. 5 is an enlarged detailed view of Fig. 4 but illustrated with the slit open.

Fig. 6 is a fragmentary enlarged detailed view of Fig. 4.

Fig. 7 is a fragmentary perspective view similar to Fig. 1 but illustrating a modified form of this invention.

Fig. 8 is a fragmentary enlarged sectional view taken on the line 8—8 of Fig. 7.

The new and improved garment sleeve, in accordance with this invention, includes a sleeve body 10 having a slit 11 extended inwards from its outer end. This slit 11 is associated with means by which it may be releasably held closed. The particular means illustrated are buttons 12

2

mounted upon the material at one side of slit and engageable with buttonholes 13 in the material on the other side of the slit. The slit 11 is made in the usual way so that the material which forms 5 the slit overlaps, as shown clearly on the drawing.

A hem 15 is bent upwards and inwards from the outer end of the sleeve. Releasable means, such as basting stitches 16 are provided for holding the hem 15 so that it may be let out or moved 10 inwards very conveniently for changing the length of the sleeve. One corner 17 of the hem 15 is bent inwards so as to form an oblique end 18 to avoid the bottommost buttonhole 13 and cooperative button 12. The basting stitches 16 are 15 also extended downwards along the oblique end 18. A sleeve length scale 20 is mounted on the inner face of the sleeve along the material at one side of the slit 11. This scale 20 is imprinted to indicate the length of the sleeve. The top edge 20 21 of the hem 15 extends across the scale 20 and indicates the length of the sleeve.

The operation and use of the new garment sleeve may be understood from the following:

When it is desired to change the length of the 25 sleeve, as for example when the shirt is bought and the sleeves are too long, it is a simple matter of opening the basting stitches 16 and readjusting the width of the hem 15. The adjusted hem 15 is then sewed down with new basting stitches 16. After laundering when the sleeve shrinks, it is advisable that the length of the 30 sleeve be readjusted by again opening the basting stitches 16. When the garment is worn, it is easy to note the amount that the sleeve should 35 be extended or shortened. When the hem 15 is open, the top edge 21 may be placed against the indications on the scale 20 to obtain the length of sleeve desired.

In Figs. 7 and 8, a modified form of the invention 40 has been disclosed which is very similar to the prior form, distinguishing merely in the construction and operation of the releasable means for holding the hem 15 so that it may be conveniently let out or moved inwards for changing the length of the sleeve. This means includes 45 a group of straps 25 arranged parallel to each other at spaced points around the inner face of the sleeve. The top ends of the straps 25 are permanently secured to the sleeve by stitches 26. The top portions of the straps 25 are folded back 50 and forth forming an accordion portion 27. These accordion portions are held closed with basting stitches 28. Snap fastener elements 29 are mounted upon the bottom ends of the straps 55

25 and are cooperative with complementary snap fastener elements 30 mounted on the hem 15.

In other respects this form of the invention is similar to that previously shown and like reference numerals identify like parts in each of the several views.

When it becomes necessary to change the length of the sleeve it is merely necessary to open the basting stitches 28 of the straps 25 and refold the accordion portions 27 so as to extend or take in the straps 25 to change their lengths and so indirectly control the points of support of the snap fasteners 29 and 30. This controls the width of the hem 15 and indirectly the length of the sleeve.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a garment sleeve having a slit extended inwards from its outer end, means for releasably holding said slit closed, a hem bent upwards and inwards from the outer end of said sleeve, releasable means for holding said hem so that it may be let out or moved inwards for changing the length of said sleeve, and a sleeve length scale mounted on the inner face of said sleeve, said releasable means comprising a group of straps mounted at their upper ends within said sleeve at points around said sleeve, said straps

having accordion portions by which they may be extended or retracted, basting stitches for holding said accordion portions closed, and fastening elements on the bottom ends of said straps and cooperative with complementary fastening elements on said hem, said means for holding said slit closed comprising buttons and buttonholes, and one corner of said hem being bent inwards so as to avoid blocking the lowermost button and buttonhole and permitting extension of said hem free of obstacles from said buttonhole.

2. In a garment sleeve having a slit extended inwards from its outer end, means for releasably holding said slit closed, a hem bent upwards and inwards from the outer end of said sleeve, releasable means for holding said hem so that it may be let out or moved inwards for changing the length of said sleeve, and a sleeve length scale mounted on the inner face of said sleeve, said releasable means comprising a group of straps mounted at their upper ends within said sleeve at points around said sleeve, said straps having accordion portions by which they may be extended or retracted, basting stitches for holding said accordion portions closed, and fastening elements on the bottom ends of said straps and cooperative with complementary fastening elements on said hem, said fastening elements comprising snap fasteners, said means for holding said slit closed comprising buttons and buttonholes, and one corner of said hem being bent inwards so as to avoid blocking the lowermost button and buttonhole and permitting extension of said hem free of obstacles from said buttonhole.

CHARLES SOLOMON.
